UNITED STATES PATENT OFFICE

2,676,388

METHOD FOR ERECTING TOWER CRANES

André Faure and Antoine Faure, Firminy, France

Application January 13, 1949, Serial No. 70,785

Claims priority, application France April 20, 1948

4 Claims. (Cl. 29—148)

1

Our invention relates to tower cranes of the type described in our prior specifications corresponding to the basic French Patents 806,727 of May 25, 1936, and 815,733 of December 31, 1936, the mounting of which cranes is ensured by means of a superposition of sections forming the tower, that are introduced in succession into the part of the crane forming the base thereof and are connected with the immediately overlying sections to be raised therewith by a suitable mechanism so as to produce thus a step by step erection of the tower to the desired height.

When the crane is of somewhat considerable size, its base is too large for it to be possible to transport it any longer as a unit and this requires as already disclosed in our copending application corresponding to French Patent 979,027 filed on March 13, 1942, delivered on December 6, 1950, and entitled, "Improvements in Tower Cranes Constituted by Superposable Elements That Are Easily Mounted and Dismantled," constituting said base by means of a number of easily transportable parts that are assembled with one another at the place of erection and operation. On the other hand the sections of the tower are also too heavy and too cumbersome to allow their easy displacement by mere manpower with a view to their introduction into the base and their successive raising through same.

Our invention relates to a novel design and a novel manner of mounting such tower cranes.

It consists chiefly in designing the head of the power crane in a manner such that it may allow before its mounting, its transformation, in association with a counter jib, into an auxiliary crane that is used for cooperation in the mounting of the base and also for the unloading of the necessary machinery.

A further object of our invention consists in providing one or more suitably designed carriages, the number of which is preferably two, of which one supports at the moment of the mounting of the base the above mentioned auxiliary crane, said carriages being adapted to run over a track positioned along the desired axis of translation of the crane and serving subsequently as the platforms on which are assembled the tower sections, said rolling platforms being urged in succession and alternatingly into the base of the crane. One of these carriages allows introducing a section of the tower while the other serves for the raising movement inside the base and the parts played by them are alternatingly exchanged.

Our invention will be better understood from examination of accompanying drawings, reference being made to accompanying diagrammatic

2

drawings given out solely by way of exemplification and wherein:

Fig. 1 shows the entire tower crane in its assembled position and ready for operation.

Fig. 2 shows diagrammatically at a larger scale the head of the tower.

Fig. 3 shows how this head may be used temporarily as an auxiliary crane for unloading and mounting purposes.

10 Figs. 4 to 20 illustrate various stages of operation in the mounting.

Figs. 21 and 22 show at a larger scale in elevational view, respectively in front and side elevational view, the details of the mounting of the tower sections.

15 Figs. 23 to 27 inclusively illustrate various details of the crane.

As illustrated, the head T of the crane includes a stationary pyramid-shaped part 1 (Figs. 1, 2 and 23) provided at its upper end with a pivot 1a and at its lower end with a circular guideway 1b whereby the part 2 capping the part 1 is adapted to revolve round its vertical axis. Said revoluble pyramid-shaped part 2 is provided at its upper end with a bearing 2a revolvably carried by the pivot 1a while the lower end of said part 2 carries four rollers 2b that roll over the circular rail or guideway 1b. Between the bearing 2a and the flange on the pivot 1a is inserted a ball thrust 1c. Said pivoting and revoluble part 2 or pivoting pyramid has securing points 3 and 4 for connection respectively with the jib 5 and with the counter jib 6, 6'. The stationary part 1 of the head T carries as shown diagrammatically at 7 in Fig. 2 a mechanism for the angular setting of the revoluble or pivoting pyramid 2 that carries in its turn a winch 8 providing for modifications in reach and that is designed to serve also as an auxiliary hoisting winch. As illustrated more particularly in Fig. 23, the revoluble pyramid 2 is provided with an annular flange 1d provided with an inner series of teeth meshing with a pinion 7a that may assume a rotary movement in either direction under the action of a motor 7b through the agency of a worm and worm wheel speed reducer 7c.

45 The counter jib is constituted by two sections 6 and 6' assembled in alignment with one another and interconnected through the lower hinge point 9. A counterweight 10 is mounted at the outer end of the section 6' (Fig. 1).

50 The tower P is constituted by superposed sections 12 assembled with one another.

As illustrated in Figs. 26 and 27, the base B mounted on rails 13 includes four bogies 74 constituted each by two rollers 14b carried by a common support 14c adapted to pivot round a verti-

cal axis through the agency of the pivot 14d secured to a stringer or cross member 16. The rollers of two of said bogies are provided with an annular series of teeth 14e providing for the mechanical translational movement under the control of a motor and a speed reducing gear that is not illustrated. Obviously there are two bogies behind one another on each rail.

The cross members 16 are constituted by beams carrying the pivots 14d of the bogies. To said cross members are also secured the feet 15 of the crane base through the agency of the bolts 15b. These feet 15 are made of a metal latticework and carry the compartments 17a and 17b to which they are secured through the bolts 15b.

The compartments 17a and 17b are constituted by surfaces of sheet metal that are suitably assembled and stiffened. When mounted, they are filled with steel rods that serve for the ballasting of the crane. The two compartments 17a and 17b are separated by a space housing a guiding member 26 and a winch system 19.

The guiding member 26 is constituted by a metal skeleton bolted to the compartments 17a and 17b through the bolts 17c. The guiding member is provided with rollers 26a between which may slide the sections 12 of the crane tower during the erection of the latter.

The winch 19 includes a drum 19a rigid with a toothed flange 19b adapted to be driven by the pinion 19c when it is brought into its operative position as provided through a shifting of the lever 19d in the direction of the arrow f. The pinion 19c is carried by an intermediary shaft 19e controlled by the motor 19f through the agency of the gear work 19g.

The cab 20 is secured at the desired height on one of the sides of the tower.

The mounting of such a tower crane is performed as follows with two carriages 22a and 22b, after laying a supplementary track section 23 for said carriages, said track being narrower than the track 13 on which the crane is adapted to move, while being arranged along the same axis as the latter (Fig. 22).

At the moment where the working material arrives in situ, there is assembled on one of the carriages, say the carriage 22a, the head T of the tower illustrated separated in Fig. 2. To the point 4 of the latter, is pivotally secured the counter jib and there is added a tie rod 53 so as to form at 9 between the elements 6 and 6' of the counter jib a gap that is held open by said tie rod. It should be remarked that these elements 6 and 6' of the counter jib are held in alignment for normal operation by means of a spindle engaging two cooperating eyes 6a as shown more particularly in Figs. 24 and 25, said spindle serving also as an attachment for the tie rod 24 that is used, as will be disclosed, for positioning the counter jib. The counterweight 10 is secured to the counter jib through spindles 10a and 10b.

The insertion of the tie rod 53 between the elements of the counter jib as shown more particularly in Fig. 25 is obtained through engagement thereof between the two pivots 6a that are shown in superposition in Fig. 24 for which the counter jib elements are in alignment; pulleys 6b and 6c are also secured to the ends of the smaller element of the counter jib, to allow an easy passage of the positioning cable as described hereinafter. The counter jib thus transformed into an auxiliary crane is then raised and it is held in position by means of a further tie rod 24. There is

also secured to the pivoting pyramid 2 the counterweight 10; this provides thus an auxiliary crane A the hoisting and angular setting of which are produced mechanically as shown in Fig. 3 and this auxiliary crane allows controlling any desired part of the main crane with a view to unloading it from the transportation trucks and to mounting the base.

The mounting of the tower crane is executed substantially as follows, the control cab 20 lying on the ground quite close to the location over which the base is to be mounted while a temporary connection is provided between it and the various motors controlled from said cab. For this purpose, the cab includes the starting controllers for the motors providing for the different movements of the train together with the corresponding electric resistances. The cab includes, therefore, a controller for the hoisting winch 19, a further controller for the reach-modifying winch 8 (Fig. 2) and a controller for the mechanism 7 controlling the angular setting of the jib.

Whatever may be the location of the cab, it is sufficient to establish an electric connection between the controllers and the corresponding motors in order to provide through operation of said controller, for a rotation of the different motors and a starting of the mechanism when it is desired to use same.

The first bogey is positioned and set over one of the rails forming the track 13 and it then receives through operation of the auxiliary crane A a corresponding foot 15 (Fig. 4) that is held temporarily in position by means of stays or the like suitable struts.

Use is then made of the same crane A for positioning the cross-member 16 that is assembled with the foot 15 as shown in Fig. 5; the cross-member is held by suitable wedging up members 25 until the second bogey 14 is mounted in a similar manner as shown in Fig. 6 with a second foot 15 that is assembled with the cross-member 16. The foot 15 is in its turn held by suitable struts or stays. The compartment or caisson 17a is then mounted over the feet 15 and assembled therewith as shown in Fig. 7. The same sequence of operations is then performed over the other rail to obtain a symmetrical structure.

It is then sufficient in order to finish the mounting of the base B to position the complete guide member 26 and to assemble it with the compartments or caissons 17a and 17b underlying it (Fig. 8). For this purpose, the guiding member 26 may include the raising screws 27 illustrated with further detail in Figs. 26 and 27. Said screws 27 are rigidly secured at 27a to the two ends of the cross member or lifting beam 28 and engage corresponding nuts 27b carried by the guiding member 26. Said nuts are each rigid with a bevel wheel meshing with a pinion 27c rigid with a chain wheel 27d. The compartments 17 being suitably ballasted, the winch 19 is then set on the base thus formed with the guide member 26 at the top of said base.

When the lever 19d of the hoisting winch 19 is urged in a direction opposed to the arrow f, the pinion 19c releases the toothed flange 19b and meshes with the toothed wheel 27e. It is then possible, after starting the motor 19f, to provide for the rotation of the intermediary shaft 27g carrying the toothed wheel 27e in order to control the transmission chains 27h and therethrough the rotation of the nuts 27b. The latter in their turn provide for the upward or downward movement of the screws 27 on the

cross member 28 and of the material carried by the latter.

It is thus apparent that the operation of the lever 19d provides for the selective coupling of the control motor 19f either with the hoisting winch or with the screws 27 adapted to raise the cross member 28. It should be remarked that the guiding member 26 is of the type described in our above mentioned prior specification.

The use of the auxiliary crane A is then at 10 an end and it is dismantled so as to leave on the carriage 22a only the actual head T of the crane tower. The screws 27 on the lifting beam 28 are coupled with the winch 19 that is connected with the controller housed inside the adjacent cab 20 as disclosed hereinabove. The beam 28 is then caused to sink down to ground as shown in Fig. 10, the track 23 being interrupted to this purpose so as to allow said beam 28 to fit inside it.

The carriage 22a carrying the tower head T is then urged forwardly into vertical register with the axis of the crane over the beam 28 and the system including the carriage and the tower head is then raised through the raising of the beam 28 as shown in Fig. 12. Only the head of the tower is then connected with the guiding member 26 on the base B and remains hanging therefrom after the raising beam 28 has been lowered with the carriage 22a (Fig. 13). During this time a section 12 of the tower has been assembled on the other carriage 22b; the carriage 22a is removed over the rails and is replaced by the said carriage 22b that is brought into vertical register with the axis of the crane, over the beam 28 under the base B (Fig. 14).

The raising beam 28 is again raised together with the carriage 22b, the section 12 and the head T that is now assembled with said section 12 after it has been disconnected with reference to the guiding member 26. The assembly is securely fixed to the base B in this further raised position (Fig. 15). The assembling of the different sections 12 of the tower is illustrated in Fig. 27: there are used to this purpose bolted fish plates 45 12b. Said figure also shows in dot-and-dash lines a cross beam 33a carrying the pulley 33b over which passes the cable 33 that is attached at 33c to the drum 19a of the hoisting winch.

The jib 5 can now be mounted as well as the counter-jib 6-6'.

The sections of the jib are assembled on the ground and its normally outer end rests on the available carriage 22a (Fig. 16). The screws 27 are disconnected with reference to the winch 55 19 and a cable 29 is secured to the drum of said winch and caused to pass from said drum on to guiding pulleys to be finally attached to the end of the jib 5 adjacent to its hinge point 3.

The actuation of the winch 19 produces then 60 a rising movement of the rear end of the jib, the above mentioned hinge 3 of which is brought into position on the head T of the tower 8 which allows introducing the spindle that is to connect permanently the foot of the jib to the head of the tower. The cable 29 is then caused to pass over the tackle gear 39 inserted between the end of the stay 32 of said jib and the upper end of the tower head (Fig. 17). The jib should be previously fitted with all the cables that may be necessary.

Through actuation of the winch 19, the jib is now brought into its final horizontal position (Fig. 18) and its stay 32 is connected with the 75

upper end of the head of the tower T after removal of the intermediate tackle.

The counter-jib 6-6' is then mounted in a similar manner and there is finally obtained a system as illustrated in Fig. 19. The cable 29 that has been used for raising in succession the jib and the counter-jib is then removed and taken off the winch drum 19 to which the raising jack screws 27 are again coupled. The rigid connection with the tower section provided as mentioned with reference to Fig. 14 is cut out so as to allow a downward movement of the lifting beam 28 together with the carriage 22b.

By using in alternation the carriages 22a and 15 22b, it is possible to mount in succession the different sections 12 while proceeding as disclosed hereinabove, the different sections being assembled together so as to obtain a tower T of the desired height. The last carriage which has 20 been used for raising the last section may thus remain in the assembly as shown in Fig. 20 and it is then rigidly secured to the base in order to form the connecting member for the system including the tower T and the base B.

The tower crane being thus erected, the hoisting cable 33 is fitted through its securing to the winch 19 after a final disengagement of the screws 27 the beam 28 that is locked in its upper position.

30 There only remains now to secure the controlling cab 20 that was up to the moment considered laid on the ground in proximity with the location of the crane; to this purpose the temporary connection between the winch motor and the controller located in said cab is cut out, the cab is hooked to the tackle block of the crane that raises said cab through actuation of the winch by a hand operated crank provided to this purpose and the lifting of the cab continues up to the desired level at which it is secured to the suitable side of the tower.

To ensure the lifting of said cab, it is also possible to resort to an auxiliary controller for operating the winch, which arrangement would do away with hand control.

What we claim is:

1. A method for erecting a wheeled tower crane adapted to move over rails and including a base, a tower, a jib, a counter jib and a tower head to which said jib and counter jib are to be pivotally secured, consisting in providing a narrow track between the rails that are to carry the tower crane, mounting the tower head without its jib and counter jib on a carriage adapted to run over the narrow track, pivotally securing the disassembled counter jib to the tower head on the carriage to form a small auxiliary crane running over said narrow track, incorporating to said auxiliary crane auxiliaries required for hoisting purposes, positioning a plurality of bogies over the crane rails, causing the auxiliary crane on the narrow track to lay crane base feet over the different bogies, staying the system of feet and bogies, using the auxiliary crane for positioning a cross member between the base feet, using the auxiliary crane to lay a guiding member over the feet to form a unitary base structure with said feet and bogies, laying longitudinal compartments through the agency of the auxiliary crane over said unitary structure, causing the auxiliary crane to lay a winch on said guiding member, dismantling the auxiliary crane to leave on the carriage only the head of the crane tower, and raising the tower, tower head and jib

and counter jib into position over the base erected thus through the agency of the auxiliary crane.

2. A method for erecting a wheeled tower crane adapted to move over rails and including a jib, a counter jib, a tower head to which said jib and counter jib are to be pivotally secured, a base including bogies, feet, lower cross members, staying the feet and upper guiding members staying the upper ends of the feet, a self-hoisting body including raising jacks, a lifting beam carrying same, a winch and a plurality of sections to be superposed between the base and the head, said method consisting in providing a narrow track between the rails that are to carry the tower crane, mounting the tower head without its jib and counter jib on a carriage adapted to run over the narrow track, opening the counter jib and staying it into a bracket shape, pivotally securing the disassembled bracket-shaped counter jib to the tower head on the carriage to form a small auxiliary crane running over said narrow track, incorporating to said auxiliary crane auxiliaries required for hoisting purposes, positioning a plurality of bogies over the crane rails, causing the auxiliary crane on the narrow track to lay crane base feet over the said bogies, staying the system of feet and bogies, using the auxiliary crane for positioning a cross member between the base feet, using the auxiliary crane to lay a guiding member over the feet to form a unitary base structure with said feet and bogies, laying longitudinal compartments through the agency of the auxiliary crane over said unitary structure, causing the auxiliary crane to lay a winch on said guiding member, dismantling the auxiliary crane to leave on the carriage only the head of the crane tower, and raising the tower, tower head and jib and counter jib into position over the base erected thus through the agency of the auxiliary crane.

3. A method for erecting a wheeled tower crane adapted to move over rails and including a jib, a counter jib, a tower head to which said jib and counter jib are to be pivotally secured, a base including bogies, feet, lower cross members, staying the feet and upper guiding members staying the upper ends of the feet, a self-hoisting body including raising jacks, a lifting beam carrying same, a winch and a plurality of sections to be superposed between the base and the head, said method consisting in providing a narrow track between the rails that are to carry the tower crane, mounting the tower head without its jib and counter jib on a carriage adapted to run over the narrow track, opening the counter jib and staying it into a bracket shape, pivotally securing the disassembled bracket-shaped counter jib to the tower head on the carriage to form a small auxiliary crane running over said narrow track, incorporating to said auxiliary crane auxiliaries required for hoisting purposes, positioning a plurality of bogies over the crane rails, causing the auxiliary crane on the narrow track to lay crane base feet over the said bogies, staying the system of feet and bogies, using the auxiliary crane for positioning a cross member between the base feet, using the auxiliary crane to lay a guiding member over the feet to form a unitary base structure with said feet and bogies,

5 laying longitudinal compartments through the agency of the auxiliary crane over said unitary structure, causing the auxiliary crane to lay a winch on said guiding member, dismantling the auxiliary crane to leave on the carriage only the head of the crane tower, returning the carriage into register with the axis of the crane and raising the tower head through the agency of the jacks, connecting the tower head transiently with the guiding member, setting the different sections of the tower in succession on the carriage and on a second carriage adapted to run over the narrow track, causing the jacks to raise said sections successively and in alternation off the two carriages carrying them, assembling together the different sections and the head, raising the assembly into its raised position on the base, and raising the jib and counter jib into their final positions for which they are pivotally secured to the tower head in its raised position.

4. A method for erecting a wheeled tower crane adapted to move over rails and including a base, a tower, a jib, a counter jib and a tower head to which said jib and counter jib are to be pivotally secured, consisting in providing a narrow track between the rails that are to carry the tower crane, mounting the tower head without its jib and counter jib on a carriage adapted to run over the narrow track, pivotally securing the disassembled counter jib to the tower head on the carriage to form a small auxiliary crane running over said narrow track, incorporating to said auxiliary crane auxiliaries required for hoisting purposes, positioning a plurality of bogies over the crane rails, causing the auxiliary crane on the narrow track to lay crane base feet over the said bogies, staying the system of feet and bogies, using the auxiliary crane for positioning a cross member between the base feet, using the auxiliary crane to lay a guiding member over the feet to form a unitary base structure with said feet and bogies, laying longitudinal compartments through the agency of the auxiliary crane over said unitary structure, causing the auxiliary crane to lay a winch on said guiding members, dismantling the auxiliary crane to leave on the carriage only the head of the crane tower, using the above mentioned carriage and a further carriage rolling over the narrow track for raising in succession through the operation of raising means carried by the base the tower head and the successive tower elements alternatingly through the agency of either carriage, the successively raised elements raising the preceedingly raised element and being rigidly connected therewith, and raising the jib and counter jib into position with reference to the raised head for pivotally securing them thereto.
